UNITED STATES PATENT OFFICE.

WILLIAM F. KIESEL, JR., OF ALTOONA, PENNSYLVANIA.

SIDE FRAME FOR FREIGHT-CAR TRUCKS.

Application filed November 20, 1922. Serial No. 602,138.

To all whom it may concern:

Be it known that I, WILLIAM F. KIESEL, Jr., a citizen of the United States, and resident of Altoona, county of Blair, State of Pennsylvania, have invented certain new and useful Improvements in Side Frames for Freight-Car Trucks, of which the following is a specification.

The present invention relates to railway car trucks of the freight car type and particularly to the side frames thereof.

The improvement in truck side frames which the present invention is designed to effect resides particularly in the construction and form of the lower bar, or chord, of the frame, that is, the bar which supports the bolster and springs. Heretofore the lower part of this bar, that is, the part under the springs has been made entirely as a box section; and the webs of the diagonal channel shape members have joined the bottom of said box section. In this construction the theoretical length of the lower bar is excessively great requiring excess metal to resist the stresses. Theoretically, this lower bar, or chord, should have the form of a catenary in order to provide maximum strength with a minimum weight of metal. It is an object of the present invention to produce a frame in which the lower chord approaches the catenary form as nearly as it is possible to make it and still leave the necessary spaces for the springs, bolsters, etc. A further object of this invention is to reinforce the web of the lower chord in such a way that the said web will be placed throughout in the location of least angularity and distortion and the line connecting the neutral axes of the sections will be close to the theoretical line of least bending strain in the lower chord.

Other objects and features of novelty will be apparent from the description and drawings, in which:

Figure 1 is a side view, partly in section, of a truck side frame constructed in accordance with the present invention;

Figure 2 is a top plan view;

Figure 3 is a vertical sectional view taken substantially on the line 3—3 of Figure 1; and

Figures 4 to 10 are sectional views taken respectively on the section lines bearing the same numerals as the corresponding figures.

The frame illustrated by the drawings consists of a one-piece casting formed with an upper chord 10, a lower chord 11, upright struts 12, and end portions 13 having their lower faces shaped to fit over a pair of journal boxes. The struts and chords define a substantially rectangular opening for the bolster, spring plank and springs and substantially triangular side openings. Preferably the upper chord 10 is of channel or U-section opening downwardly (see Figures 3 and 7) and the struts 12 are of U-section opening towards the triangular spaces (see Figure 8). The lower chord 11, in which the present invention particularly resides, depends from the ends of the upper chord in the form of a catenary as nearly as practicable. It consists of inclined portions 14 extending downwardly from the upper chord and joining a substantially horizontal portion 15 defining the bottom of the bolster opening. Preferably the inclined portions 14 are of channel or U-section opening upwardly, or towards the triangular spaces, with the web at the bottom. As shown in Figures 1 and 9, these inclined portions each have a web 14^a with upwardly extending marginal flanges 14^b, having beads 14^c at their upper edges. As shown in Figures 1, 3 and 4, the bottom or horizontal portion is also of U-section but opening downwardly, the web being at the top. Thus the web 15^a has the depending flanges 15^b which extend throughout the length of said portion, and at their ends are tapered to join the inclined portions adjacent the lower ends of the struts 12. Preferably these flanges 15^b have reentrant flanges 15^c. If desired, to provide additional strength, the central portions of the reentrant flanges 15^c may be joined, as shown at the bottom of Figure 3, thus forming a box section at this point. The web 15^a of this bottom portion may be extended laterally to provide side flanges 18 and these side flanges and the side flanges 15^b may be reinforced by vertical webs 16.

One of the principal features of this construction resides in locating the web 15^a at the top of the horizontal portion and joining it to the webs of the inclined portion so that the inclined webs 14^a and the bottom web 15^a form one continuous web approaching in length the desired catenary curve.

Heretofore, the inclined webs have joined a web at the bottom of the horizontal portion, thereby requiring a heavier construction because of the length along the web from end to end of the side frame.

In the present construction the web of the lower chord is located throughout its extent in the position of least angularity and distortion, and the line connecting the neutral axes of the sections is close to the theoretical line of least bending strain in the chord. Hence it follows that said chord can be formed with less metal than is possible in the prior constructions and at the same time 15 be as strong or stronger.

Although one embodiment of the invention has been described in detail it is to be understood that the invention is not thus limited, but includes modifications and 20 changes that come within the scope of the appended claims.

Having thus described my invention what I claim as new and desire to secure by Letters Patent is:

25 1. A truck side frame comprising an upper chord, a lower chord, and upright struts defining with said chords a central bolster opening, said lower chord depending from said upper chord as nearly as practicable in 30 the form of a catenary and having a U-section, opening downwardly below said bolster opening, and opening upwardly through the remainder of its extent.

2. A truck side frame including a lower 35 chord comprising a horizontal web forming a seat for the spring plate and inclined webs extending from said horizontal web to the upper chord of the frame, said inclined webs having upwardly extending flanges of substantially uniform width and said horizontal web having downwardly extending flanges.

3. A truck side frame including a lower 45 chord comprising a horizontal web forming a seat for the spring plate and inclined webs connected to the upper chord of the frame, said inclined webs having upwardly extending flanges throughout the length thereof and said horizontal web having downwardly 50 extending flanges terminating in reentrant flanges.

4. A truck side frame including a lower 55 chord having a horizontal web forming a seat for the spring plate and inclined webs joining said horizontal web to the upper chord of the frame, said inclined webs having upwardly extending flanges throughout the length thereof and said horizontal web having downwardly 60 extending side flanges terminating in reentrant flanges, the central portion of said reentrant flanges being connected to form a box section.

5. A truck side frame having a central 65 bolster opening and a lower chord having a substantially horizontal web portion defin-

ing the bottom of said opening and having inclined web portions connected to the upper chord of the frame, said horizontal web portion having downwardly extending flanges terminating in reentrant flanges, the 70 central portions of said reentrant flanges being connected to form a box section.

6. A truck side frame comprising channel bar sections forming an upper chord, a lower chord depending therefrom, and upright struts joining intermediate points of said chords, said chords and struts forming a central bolster opening and substantially triangular side openings, said lower chord having a U-section opening downwardly below 80 said bolster opening and opening upwardly between said struts and upper chord.

7. A truck side frame comprising channel bar sections forming an upper chord and a lower chord depending therefrom, and upright struts joining intermediate points of said chords, said chords and struts forming a central bolster opening and side openings, the portion of said lower chord below said bolster opening consisting of a horizontal 90 web and downwardly extending flanges, said flanges having reentrant flanges, and the central portions of said reentrant flanges being connected to form a box section.

8. A truck side frame comprising U-section bars forming an upper chord, a lower chord, and two upright struts between said chords, said chords and struts defining a central bolster opening and substantially triangular side openings, the U-section of said 100 lower chord opening downwardly below said bolster opening and having reentrant flanges connected together directly below said bolster opening to form a box section.

9. A truck side frame consisting of an integral casting composed of an upper chord, a lower chord depending from the ends thereof, upright struts joining intermediate points of said chords, and end portions adapted to bear on a pair of journal boxes, 105 said chords and struts forming a substantially rectangular bolster opening and substantially triangular side openings, said lower chord including a substantially horizontal web with downwardly extending flanges below said bolster opening, the central portions 110 of said flanges being connected to form a box section.

10. A truck side frame consisting of an integral casting composed of an upper chord, a lower chord depending from the ends thereof, upright struts joining intermediate points of said chords, and end portions adapted to rest on a pair of journal boxes, 120 said chords and struts forming a central bolster opening and substantially triangular side openings, said lower chord having a U-section with a substantially horizontal web and downwardly extending flanges below 125 said bolster opening and with inclined webs 130

having upwardly extending flanges of substantially uniform width between said upper chord and struts.

11. A truck side frame consisting of 5 channel bar sections forming an upper chord, a lower chord depending from the ends thereof, upright struts joining intermediate points of said chords, and end portions adapted to rest on a pair of journal 10 boxes, said chords and struts forming a central rectangular bolster opening and substantially triangular side openings, said lower chord having a U-section with a substantially horizontal web and downwardly 15 extending flanges below said central opening and with inclined webs and upwardly extending flanges of substantially uniform width between said upper chord and struts.

12. A truck side frame consisting of an integral casting composed of an upper chord, a lower chord depending from the ends thereof, upright struts joining intermediate 20 points of said chords, and end portions having under surfaces adapted to bear on a pair of journal boxes, said chords and struts forming a central substantially rectangular bolster opening and substantially triangular side openings, said upper chord and struts having a U-section 25 opening downwardly and having a U-section opening downwardly and

towards said triangular openings respectively, said lower chord having an inwardly opening U-section between its points of connection with said upper chord and said struts and having a downwardly opening U-section with a substantially horizontal web below 35 said bolster opening.

13. A truck side frame consisting of an integral casting composed of an upper chord, a lower chord depending from the ends thereof, upright struts joining intermediate 40 points of said chords, and end portions adapted to bear on a pair of journal boxes, said chords and struts forming a central substantially rectangular bolster opening and substantially triangular side openings, said 45 upper chord and struts having a U-section opening downwardly and towards said triangular openings respectively, said lower chord having an inwardly opening U-section between its points of connection with said upper chord and said struts and having a substantially horizontal web below said bolster opening with downwardly extending flanges, the central portions of said flanges being connected to form a box section. 50 55

In testimony whereof I hereunto affix my signature.

WILLIAM F. KIESEL, JR.
